PULSATORY PERCUSSIVE DRILL.

1,144,990.

Specification of Letters Patent.

Patented July 6, 1915.

Application filed June 29, 1912. Serial No. 706,608.

To all whom it may concern:

Be it known that I, LEWIS C. BAYLES, a citizen of the United States, residing in Easton, in the county of Northampton and 5 State of Pennsylvania, have invented certain new and useful Improvements in Pulsatory Percussive Drills, of which the following is a specification.

This invention relates to percussive drills 10 and more particularly to that type of drill wherein the piston is reciprocated by pulsations produced by a reciprocating pump or compressor directly connected with the drill cylinder.

15 One object of the present invention is to produce a drilling mechanism of this type of great simplicity and great efficiency and a further object is to so construct such a drill that air from the drill may be conveyed through the drill steel to effectively remove rock cuttings and dust therefrom.

20 With these objects in view I have devised a drilling mechanism a practical embodiment of which is shown in the accompanying 25 drawing in which the figure shows a side view of the drilling mechanism partly in section and partly in elevation.

The drill itself as shown comprises a cylinder 1 in which reciprocates a piston 2 the 30 forward part of which is reduced in diameter forming a shank 3 which slides in a sleeve 4 of smaller diameter than the main cylinder. In the sleeve 4 are the cylindrical holes or chambers 5, which open into 35 the forward part of the cylinder 1 forming a part thereof. A port 6 opens from the main part of the cylinder at a point just uncovered by the piston at the end of its forward stroke and from this port a passage 7

40 leads to the forward end of the cylinder to the other side of the large diameter portion of the piston. In the passage 7 is seated a spring pressed plate check valve 8 which allows fluid to pass from the back 45 to the front end of the cylinder but not in the reverse direction. Forward of the cylinder is a front head 9 in which is rotatably mounted a steel holding sleeve 10 which is adapted to hold the hollow drill steel 11.

50 The extreme forward part of the piston is provided with spiral flutes 12 which slide in a similarly grooved bushing in the rear end of the steel holding sleeve 10. The piston has a central bore 14, the forward part 55 of which is of smaller diameter and reg-

isters with the bore in the drill steel 11 and the rear portion of which is of larger diameter and is provided in its rearmost end with a grooved bushing 15 in which slides a rifle bar 16 which rotates in the back head 60 of the drill and is provided with a ratchet rotating mechanism 17 of ordinary construction. The rifle bar 16 and the bushing 15 are more or less loosely fitted so that there is a certain amount of room for leakage from the back part of the cylinder through the bore of the piston. From the chamber 5 ports 18 open into the interior of sleeve 4 at a point cleared by the smooth portion of the smaller diameter part 3 of 70 the piston at the end of its rearward stroke. At the rear end of the cylinder is a port 19 which leads by a pipe 20 to the driving pump or compressor of the drill. This comprises as shown a cylinder 21 in which reciprocates a piston 22, the upper end of the cylinder being in direct communication with the pipe 20. The lower part of the piston and cylinder are of larger diameter 75 forming in effect a second cylinder and piston which operate as a pump for forcing air into the drill operating portion of the cylinder, air being taken in on the down stroke through the plate valve 23 and forced into the drill operating portion of the cylinder on the up stroke through a plate valve 24 and a passage 25. The piston 22 is reciprocated by ordinary crank means (not shown) through a reduction gear 26, 80 of ordinary construction (not shown in detail) and motor 27 mounted on a wheeled truck 28.

In operation the reciprocation of the piston 22 causes a corresponding reciprocation of the piston 2, the up stroke of the piston 22 causing the piston 2 to move forwardly striking a blow on the drill steel. At the end of the forward stroke of the piston 2 the port 6 is uncovered allowing pressure to be equalized in the two ends of the cylinder 1. The down stroke of piston 22 retracts the piston 2, the air in chamber 5 and in the front part of the drill cylinder expanding as the piston 2 moves backward. 100 As soon as the ports 18 are uncovered by the smooth portion of the smaller diameter part of the piston the air in chamber 5, which is still under some compression, will escape into the steel holding sleeve and from thence will exhaust out through the hollow 110

drill steel blowing the rock cuttings and the dust from the hole. A small amount of air is constantly escaping from the back part of the cylinder around the rifle bar 16 into the bore 14 of the piston 2 and passing through the bore of the drill steel to the hole. The air lost in this way from the drill cylinder is constantly supplied by the pump formed by the larger diameter portions of the cylinder 21 and piston 22 this pump being of such capacity that the compression in the drill cylinder is constantly maintained considerably above atmospheric pressure. It is to be noticed that this pump delivers its air to the drill cylinder during the whole forward stroke of the piston 2, in this way adding to the force of the blow of the piston. If the air were delivered to the drill cylinder on its backward stroke it is apparent that the backward motion of the piston 2 would be considerably retarded.

By the use of the present construction a heavy and efficient blow is given to the drill steel and an ample supply of air forced through the drill steel to efficiently clear the hole, there being a small constant flow through leakage around the rifle bar through the piston and a periodically greater flow of a momentary and sudden nature through the ports 18 at the end of each back stroke of the piston 2.

It is to be understood that the present

showing and description discloses only one specified modification of my invention and other forms and modifications are included 35 in the spirit and scope of the invention as expressed in the claims.

What I claim is:

1. In combination, a driving cylinder and piston, a percussive tool comprising a cylinder and a piston driven by the pulsations of said driving piston, a hollow drill steel, means for conveying fluid from said cylinder through said steel, and a pump for supplying additional fluid between said 45 driving and driven pistons during the forward stroke of said driven piston.

2. In combination, a driving cylinder and piston, a percussive tool comprising a cylinder and a piston driven by the pulsations 50 of said driving piston, a hollow drill steel, a bore through said driven piston communicating with said hollow drill steel, a rifle bar loosely engaging the rear end of the piston bore and admitting air from the rear 55 end of the cylinder to said hollow drill steel, and pumping means for supplying additional fluid between said driving and driven pistons during the forward stroke of said driven piston.

LEWIS CONDICT BAYLES.
